UNITED STATES PATENT OFFICE

THOMAS B. MINYARD, OF GREENWOOD, MISSISSIPPI

GRAVEL WELL SCREEN

Application filed January 16, 1930. Serial No. 421,237.

- This invention relates to improvements in screens for use upon the lower ends of well pipes and is designed for use in connection with water, oil or gas wells.
- 5 The primary object of the present invention is to provide a screen which will effectively stop sand from entering a well line pipe and which will not corrode, stop up or wear out.
- 10 Another object of the invention is to provide an improved well pipe screen from which sand may be readily removed by pumping water back through the well line pipe.
- 15 Still another object of the invention is to provide in association with the screen device adapted to be attached to the lower end of a well line pipe, a resilient body which connects between the line pipe and the 20 wall of the well hole permitting the washing out from the lower end of the well hole of mud but preventing mud and cavings from falling back into the bottom of the well around the screen.
- 25 The present invention broadly contemplates the provision of a screen consisting of a pair of perforated pipe sections, one being placed within and being of materially less diameter than the other, both of the pipes 30 being attached to the lower end of a line pipe and having packed therebetween selected and clean gravel.
- The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the 35 appended claims.

In the drawings:—

Figure 1 is a longitudinal sectional view through one form of the gravel well screen embodying the present invention, the same 50 being shown in a well hole.

Figure 2 is a sectional view taken upon the line 2—2 of Figure 1.

Figure 3 is a sectional view taken upon the line 3—3 of Figure 1.

Figure 4 is a modified form of the structure shown in Figure 1, this form being for use in small diameter bores.

Figure 5 is a further modified form of the structure shown in Figure 1, this modified form being for very large wells and so designed as to prevent sticking in the mud and sand therein.

Referring more particularly to the drawings wherein like numerals of reference indicate corresponding parts throughout the several views, the numerals 1, 2 and 3 indicate respectively strata of shale, sand and hard packed earth such as is frequently encountered in the bottom of a well, the fluid to be moved flowing into the well hole from the sand stratum. The function of the present screen device is to prevent the sand from this stratum entering the well line pipe.

In Figure 1 the well line pipe is indicated by the numeral 4. The gravel screen structure constituting the present invention is shown attached to the lower end of the line pipe 4 and is indicated as a whole by the numeral 5. As shown this screen consists of an inner tube or pipe 6 and an outer pipe 7 which pipes should properly be of brass or bronze but may be of the same material as the line pipe. Both of these tubes 6 and 7 are provided throughout with apertures either in the form of circular openings or in the form of longitudinally extending slots, these openings being indicated in both tubes by the numerals 8.

The inner tube 6 is connected with the lower section of the line pipe 4, which section is exteriorly threaded as indicated at 9, by the collar 10, this inner tube being of the same diameter as the line pipe as shown. Interposed between the tube 6 and the line pipe 4 is a centrally apertured plate 11 through which passes a wash pipe 12, this wash pipe extending to the lower end of the screen as will be hereinafter described.

Surrounding the lower end of the line pipe 4 and threaded thereon is a bushing 13, this 100

bushing being maintained in place by and between the collars 10 and 14, the collar 14 being threaded onto the line pipe 4 and located above the collar 10 and the bushing as shown.

5 The bushing 13 is exteriorly threaded and is threaded into a collar 15, this collar also receiving the exteriorly threaded upper end of the outer tube 7.

10 At its lower end the inner tube 6 has coupled thereto by means of a collar 16, a nipple 17 between which and the tube 6 a centrally apertured plate 18 is secured through which the lower end of the wash pipe 12 passes as shown. The lower end of this nipple 17 has connected therewith by means of a second collar such as is indicated at 19, a second nipple 20 between which and the nipple 17 a centrally apertured valve plate 21 is secured 15 against the lower side of which a downwardly opening spring pressed valve 22 is held.

20 The lower nipple 20 is exteriorly threaded to receive a lower bushing 23, which bushing is exteriorly threaded as is also the adjacent end of the outer tube 7 to receive with the outer tube a set shoe 24 which as shown is in the form of a broad annular body the lower edge of which is sharpened as indicated at 25 so as to cut into the hard pan 3 25 in the bottom of the well. Before closing one end of the double walled body 5 there is placed between the tubes constituting the walls thereof clean, selected gravel 26, the space between these tubes being completely 30 filled as shown. Disposed between the tubes 6 and 7 are spacing or guide spiders 27 which serve to prevent deformation of the tubes 6 and 7 which make up the inner and outer walls of the screen.

35 40 In order to prevent soft mud and other undesirable matter from getting down into the lower part of the well bore between the screen structure 5 and the sand stratum there is secured to the upper bushing 13 and about the line pipe 4 a heavy flexible ring 28 which is preferably formed of rubber, suitable screws or bolts 29 serving to secure the inner portion of this ring to the top of the bushing 13 in the manner shown.

45 50 While I have shown only a single length of tubing for the inner and outer walls of the gravel screen structure it is of course to be understood that any number of lengths of this tubing may be employed to increase or decrease the length of the gravel screen as desired.

55 60 When a well pipe equipped with the gravel screen embodying the present invention is being placed in position in a well bore compressed air may be forced down through the wash pipe 12 or through the line pipe as desired to force the sand in the bore out of the way to permit the screen to take up its proper position therein and as the screen is lowered 65 the flexible ring 28 which acts in the nature

of a valve will permit mud and water to pass up around the line pipe. After the screen has been set in the bottom of the well water may be forced down through the wash pipe for discharge down through the valve 22 and out into the area surrounding the screen 5 washing out the screen and forcing mud up past the valve 28 so that only clean sand may be left in the lower part of the well. When all of the mud has been washed from around the outside of the screen and the pumps forcing the water through the wash pipe 12 have been stopped the flexible ring or valve 28 will engage the wall of the well hole and prevent cavings and mud from above the sand stratum falling back around the gravel screen.

70 75 80 85 90 From the foregoing it will be seen that after the well pipe and screen have been set in the manner described only clean sand will surround the screen 5 and as suction is applied to the line pipe water, oil or whatever substance is being removed from the well will be sucked through the gravel screen to be drawn up through the line pipe free of sand and other matter.

95 100 105 110 115 In Figure 4 a slightly modified form of the structure shown in Figure 2 is illustrated. In this form the over-all diameter of the gravel screen structure which is here indicated as a whole by the numeral 30 is the same as the line pipe 31, the outer tube 32 of this form of the invention being coupled to the line pipe by a collar 33 between which and the adjacent end of the line pipe a bushing 34 is held, the inner tube 35 which is of materially smaller diameter than the line pipe being threadably secured at its upper end in the bushing 34 in the manner shown. The flexible member or valve 36 which surrounds the lower end of the line pipe is here secured directly to this pipe. The elements making up the lower part of this modified form of screen are the same and are coupled together in exactly the same way as those in the screen shown in Figure 1 and indicated generally by the numeral 5, these elements being indicated by numerals corresponding to those in Figure 1 each of which is, however, distinguished from the numerals in Figure 1 by an α' .

120 125 130 135 In Figure 5 a still further modification of the structure shown in Figure 1 is illustrated, this modified form of the screen being designed for use in relatively large wells where a greater amount of screening material is necessary and where the possibilities of the screen becoming stuck are greater. In this form of screen the line pipe which is here indicated by the numeral 37 has a substantial portion of its lower end perforated as indicated at 38 and at the upper and lower ends of this perforated area it is provided with the screw threads 39 and 40. This perforated lower area of the line pipe constitutes the

inner portion of the screen structure which is here indicated generally by the numeral 41.

The outer perforated tube 42 of this form 5 is of slightly greater diameter at its lower end than at its upper end and is interiorly threaded at its upper end as shown to receive a bushing 43 through which the line pipe 37 passes. The perforated lower portion of the 10 line pipe 37 is formed separate from the upper portion thereof at the point where the threads 39 are formed, the upper portion of the pipe having corresponding threads thereon and these two threaded areas are coupled 15 by the collar 44 which in the assembled structure is disposed beneath the bushing 43 in the manner shown. A flexible annular member 45 constituting a valve, surrounds the pipe line 37 in the manner shown and is secured by means of suitable bolts or screws 46 to the bushing 43, as shown.

Threaded upon the lower end of the line pipe 37 is a lower bushing 47 which is exteriorly threaded for engagement with 25 threads formed in the interior wall of a set shoe 48, this set shoe receiving the lower end of the outer cylinder 42 and being secured thereto by suitable bolts or rivets 49.

From the foregoing it will be readily seen that the tapered screen is so designed that the outer surface will be smooth throughout, particularly at the upper end so that it may be made to easily penetrate the sand and mud in the lower part of a well, it, of course, being understood that while the screen is being placed in position air will be pumped into the well so as to force sand from beneath the screen and up around the sides to make sufficient room in the bottom of the well for the screen to enter. By making this form of screen tapered as shown it will not stick in the sand like a straight screen might do if placed in a large well. The rubber mud retaining ring or valve 45 of course operates in the same way in connection with this form of the screen as described in connection with the forms shown in Figures 1 and 4.

After the tapered screen has been set the lower end of the pipe line 37 may be closed by cement or any other suitable material introduced thereinto and allowed to settle in the lower end thereof.

From the foregoing description it will be readily seen that a screen constructed in accordance with the present invention will have a much longer useful life than the usual all metal screens employed at the present time and in addition to this it is believed to be readily obvious that the present improved 55 screen may be readily washed out in the event that sufficient sand penetrates the interstices between the gravel to interfere with the operation of the screen, by reversing the flow of water through the line pipe to force it down 60 and out through the screen into the well, this

excess water entering the well being forced up past the valve surrounding the lower end of the line pipe thus cleaning out the well at the same time that it cleans the screen.

Having thus described my invention, what I claim is:—

1. A well screen, comprising a pair of perforated tubular bodies, one within and spaced from the other, means for coupling one of said bodies with a well line pipe, consisting of a threaded collar designed to span adjacent ends of the said one of the bodies and the pipe, an imperforate annular body designed to surround the well pipe, means for coupling said annular body with the upper end of the other perforated body, a flexible cup washer surrounding the well pipe and resting upon the annular body, means for securing the washer to the annular body, an imperforate annular body surrounding the lower end of the inner one of said perforated bodies and bearing against the adjacent end of the other perforated body, granular matter filling the area between said perforated bodies, and a set shoe surrounding the lower end of the outer perforated body and having threaded connection with the adjacent annular body.

2. A well screen for well line pipes, comprising a pair of perforated tubular bodies, one within the other, a collar having threaded connection with the upper end of the inner body and coupling the same with the well line pipe, an imperforate annular member surrounding the well line pipe above and engaging said collar, means for threadably coupling the upper end of the outer body with said annular member, a cup washer surrounding the pipe and resting upon and secured to the annular member, an imperforate annular body surrounding and having threaded connection with the lower end of the inner perforated body, a set shoe surrounding and secured to the lower end of the outer perforated body and having threaded connection with said annular body, granular matter filling the space between said perforated bodies, said inner body being divided adjacent its lower end, an apertured plate within the inner body and secured between the adjacent ends of the portions formed by dividing the same, and a downwardly opening valve controlling the aperture of said plate.

3. A screen for well line pipes, comprising a pair of perforated tubular bodies, one of less diameter than and within the other, an imperforate annular body surrounding and having threaded connection with the upper end of the inner one of said bodies and bearing against the upper end of the outer body, said annular body having a well pipe bearing thereagainst, a collar surrounding said well pipe, annular body and outer perforated body and securing the three together,

a cup washer surrounding the well pipe and secured thereto above said collar, an imperforate annular member surrounding and having threaded connection with the lower end of the inner perforated body and bearing against the lower end of the outer perforated body, and a set shoe surrounding the last mentioned annular member and the lower end of the outer body and having threaded connection therewith to hold the same in position.

4. A screen for well line pipes, comprising a pair of perforated tubular bodies, one within and of less diameter than the other, a collar surrounding the upper end of one of said bodies and coupling the same with a well pipe, a cup washer surrounding the well pipe adjacent the upper ends of the perforated bodies, means for closing the space between the perforated bodies at the lower ends thereof, a set shoe mounted upon the lower end of the outer body, said inner apertured body being formed to provide a pair of removable sections at its lower end, a pair of centrally apertured plates, one being interposed between one removable section and the adjacent end of the body, the other plate being interposed between the two sections, a wash water pipe extending longitudinally through the inner body and passing through the first mentioned apertured plate, and a downwardly opening valve controlling the aperture of the last mentioned one of said plates.

5. A screen for well line pipes, comprising a pair of perforated tubular bodies disposed one within the other, connecting means between said bodies at one end, means for attaching the bodies at the connected ends to a well line pipe, the inner one of said perforated bodies being exteriorly threaded at its lower end, a set shoe encircling the lower end of the outer perforated body and having screw threads formed upon its interior surface, a flat annular body having both interior and exterior threads and receiving the threaded lower end of the inner perforated body and having threaded connection between its exterior threads and the threads within said shoe, the lower end of said exterior perforated body being in abutting relation to the annular body, granular material filling the area between the perforated bodies, and a flexible washer surrounding the well pipe and disposed above the perforated bodies.

6. A screen for well line pipes, comprising a pair of perforated tubular bodies one disposed within the other, the inner one of the bodies being threaded upon its upper and lower ends, a collar threaded about the upper end of the inner body and adapted to couple the lower end of a well pipe thereto, a flat annular body adapted to surround the lower end of the well pipe and to rest upon said collar and further having threads about its outer edge for engagement with the interior of the

outer body at its upper end, a set shoe surrounding the lower end of the outer perforated body, a flat annular body threadably engaging the lower end of the inner perforated body and having threaded connection with said shoe and bearing against the lower end of the outer body, granular material filling the area between the perforated bodies, a flexible cup washer adapted to circle the well pipe and resting upon the top of the first mentioned annular body, and means for securing the cup washer to the said first mentioned annular body.

In testimony whereof, I hereunto affix my signature.

THOMAS B. MINYARD.
